UNITED STATES PATENT OFFICE.

GUY W. BLACKBURN, OF ELGIN, ILLINOIS.

SPEEDOMETER.

1,213,065.

Specification of Letters Patent. Patented Jan. 16, 1917.

Application filed April 17, 1914. Serial No. 832,434.

To all whom it may concern:

Be it known that I, GUY W. BLACKBURN, a citizen of the United States, residing at Elgin, in the county of Kane and State of Illinois, have invented a certain new and useful Improvement in Speedometers, of which the following is a specification.

My invention relates to improvements in speedometers and the like and is illustrated 10 in one form in the accompanying drawings, wherein—

Figure 1 is a front elevation; Fig. 2 is a section on an enlarged scale along line 2—2 of Fig. 1; Fig. 3 is a section along line 3—3 15 of Fig. 2; Fig. 4 is a section along line 4—4 of Fig. 2; Fig. 5 is a detail on a reduced scale of a modified form; Fig. 6 shows a detail of the adjusting means; and Fig. 7 is a section along line 7—7 of Fig. 6.

Like parts are indicated by like letters 20 throughout the several figures.

A is a speedometer housing having on the front thereof a vertical rectilinear speed dial A¹. The pointer A² travels along the dial A¹, projecting out through the slot A³ from the interior of the housing.

A⁴ is a drive shaft casing leading from any suitable rotating or moving part to the housing and containing a drive shaft A⁵ to 30 operate the speedometer.

B is a rotatable spindle driven by the shaft A⁵ and rotatably mounted at either end in the housing A.

B¹, B¹ are tapered slots in opposed sides 35 of the spindle, narrower at their bottom and becoming wider progressively toward the top.

B², B² are guide rods mounted in the housing upon which is free to slide the carriage 40 B³, which carriage carries the pointer A². On this carriage on either side of the spindle B are mounted the friction rollers B⁴, B⁵. These rollers are carried in adjustable bearings B⁶, which bearings are held in position 45 on the carriage B³ by the springs B⁷ and adjustable screws B⁸. Thus the rollers B⁴ are yieldingly pressed against the spindle B by the springs B⁷, whose tension may be adjusted by the screws B⁸. It will be noted 50 that the position of the screws and bearings is such that each roller is inclined slightly

to the spindle, and thus the two rollers as they travel along the spindle and rotate in response to the rotation thereof travel a spiral path. If, then, in the arrangement 55 shown the spindle rotates in the direction of the arrows shown in Fig. 4, the friction rollers will travel upwardly along the spindle and tend to raise the carriage, but each time the spindle comes to a point where the 60 roller is in line with the slot, the roller will drop into the slot until it strikes the stop or guide rollers B⁹. Its movement toward the spindle will thus be arrested, and it will be held above the bottom of the slot. The 65 force of gravity will then operate, and the carriage will tend to drop down. As the rotational speed of the spindle increases, the height to which the carriage will be raised 70 will also increase, and the carriage will run up the spindle until it reaches a point at which the time during which the friction rollers are out of contact with the spindle just overcomes the upward movement while the friction rollers are in contact with the 75 spindle, and the carriage will rest at that point, that is to say, for a low speed the narrow slot permits the spindle to drop down a certain distance between each lifting movement, but as the speed increases the 80 time taken to pass the roller through the slot is insufficient to permit the carriage to drop the full distance, and thus the carriage rises until the increasing width of the slot increases the time of freedom sufficient 85 to counterbalance the time of rising.

It will be noted that the holding springs permit wear of the roller without changing the adjustment of the device, because the movement of the roller toward the spindle 90 is limited by the guide rollers.

In order to prevent undue wear of the rollers and of the spindle to prevent vibration and add to the smooth running features I propose to make the diameter of the two 95 rollers unequal and also to make the diameter of each of them such that as they travel on or in contact with the spindle their contact points will progressively move in order that wear may be equal about the circumference of the rollers.

I have not illustrated any odometer such

as would be used if this device were applied to an automobile, as this forms no part of my invention.

My device might be used either for a mileage speedometer for automobiles or for a tachometer or any other situation wherein it is desired to record the velocity of moving parts. It is only necessary to calibrate the scale properly.

- 10 In Fig. 5 is shown a modified form wherein K is a spring resisting the movement of the carriage in response to the coöperation of the spindle and rollers. This spring takes the place of the force of gravity. It 15 may be described as a constant yielding force just as is the force of gravity, but it enables my device to be used in positions where it is not convenient to have the spindle vertical. Its operation is, of course, exactly the same, but possibly adjustment 20 might be more convenient because the tension of the screw can be adjusted; thus it is possible to adjust either by calibrating the scale or by adjusting the tension in the 25 spring, whereas in the vertical gravity type the only adjustment that can be made is by calibrating the scale. Thus my device would be more convenient for circumstances wherein in different speed ranges were met with.
- 30 L, L are slots in the bearing brackets whereby the bracket may be shifted to change the angularity of the roller. L¹ is a false base to which the bracket when so shifted may be attached and which slides 35 along the guide screw.

I have described the carrier or the pointer carried thereby as being free to slide along the spindle. It does not, of course, mean that either of them are mounted on the 40 spindle, merely that they are free to slide along or parallel with it and it must be understood that while the particular guide mechanism for holding the carrier to its path along the spindle is the preferred type, 45 still other suitable guide mechanisms or other parts of the present arrangement made use of for that purpose. Of course, the carrier and the pointer are both of them 50 slidable along the scale and the spindle simultaneously because the scale and spindle are parallel and both of them in permanent operative relation to the carrier and indicating pointer.

I claim:

- 55 1. A speed indicator comprising a rotating slotted spindle and means for rotating it, a carrier, and means comprising said spindle for lifting said carrier against the force of gravity.
- 60 2. A speed indicator comprising a rotating slotted spindle and means for rotating it, the effective circumference of the spindle progressively decreasing upwardly, a carrier in contact with said spindle, and means

comprising said spindle for raising said carrier. 65

3. A speed indicator comprising a carrier adapted to move vertically, means for raising said carrier, said means comprising a slotted spindle adapted to be intermittently 70 in contact with said carrier.

4. A speed indicator comprising a spindle having a slot in the surface thereof increasing in width from the lower end thereof upwardly, and a carrier free to slide parallel 75 with the axis of the spindle and in contact therewith.

5. A speed indicator comprising a vertical spindle having a slotted surface, and a carrier free to slide therealong and provided 80 with means for engaging said surface.

6. A speed indicator comprising a vertical spindle having a discontinuous surface, a carrier free to slide therealong and provided with means engaging said surface, and 85 means for rotating said spindle responsive to the rotation of the member whose speed is to be determined.

7. A speed indicator comprising a vertical spindle having a discontinuous surface, a 90 carrier free to slide therealong and provided with means engaging said surface, and a scale along which said carrier slides.

8. A speed indicator comprising a vertical spindle having a discontinuous surface, a 95 carrier free to slide therealong and provided with means engaging said surface, means for rotating said spindle responsive to the rotation of the member whose speed is to be determined, and a scale along which 100 said carrier slides.

9. A speed indicator comprising a vertical spindle having a discontinuous surface, a carrier free to slide therealong and provided with means engaging said surface, 105 a scale along which said carrier slides, and a finger on said carrier in opposition to said scale.

10. A speed indicator comprising a vertical spindle having a discontinuous surface, a carrier free to slide therealong and provided with means engaging said surface, means for rotating said spindle responsive to the rotation of the member whose speed is to be determined, a scale along which 110 said carrier slides, and a finger on said carrier 115 in opposition to said scale.

11. A speed indicator comprising a vertical spindle having a discontinuous surface, and a carrier free to slide therealong and 120 provided with means engaging said surface, said discontinuous surface decreasing in effective area upwardly.

12. A speed indicator comprising a vertical spindle having a discontinuous surface, 125 a carrier free to slide therealong and provided with means engaging said surface, and means for rotating said spindle re-

sponsive to the rotation of the member whose speed is to be determined, said discontinuous surface decreasing in effective area upwardly.

5 13. A speed indicator comprising a vertical spindle having a discontinuous surface, a carrier free to slide therealong and provided with means engaging said surface, and a scale along which said carrier slides, 10 said discontinuous surface decreasing in effective area upwardly.

14. A speed indicator comprising a vertical spindle having a discontinuous surface, a carrier free to slide therealong and provided with means engaging said surface, means for rotating said spindle responsive to the rotation of the member whose speed is to be determined, and a scale along which said carrier slides, said discontinuous 20 surface decreasing in effective area upwardly.

15. A speed indicator comprising a vertical spindle having a discontinuous surface, a carrier free to slide therealong and provided with means engaging said surface, a 25 scale along which said carrier slides, and a finger on said carrier in opposition to said scale, said discontinuous surface decreasing in effective area upwardly.

16. A speed indicator comprising a vertical spindle having a discontinuous surface, a carrier free to slide therealong and provided with means engaging said surface, means for rotating said spindle responsive to the rotation of the member whose speed is 35 to be determined, a scale along which said carrier slides, and a finger on said carrier in opposition to said scale, said discontinuous surface decreasing in effective area upwardly.

40 17. A speed indicator comprising a vertical spindle, a carrier slidably mounted and free to fall along said vertical spindle, said vertical spindle having mutilated means for intermittently connecting said carrier and said spindle, and contact members whereby the carrier may be intermittently raised and lowered along the spindle by the rotation thereof.

18. A speed indicator comprising a spindle, means for rotating it, said spindle having a slotted surface interrupting the cylindrical surface, a carrier parallel with said spindle, and a contact member on said carrier in engagement with said spindle.

55 19. A speed indicator comprising a slotted vertical spindle, the slot increasing in width upwardly, a carrier free to travel parallel with and alongside of the spindle, friction rollers mounted on the carrier in contact 60 with the surface of the spindle and inclined thereto, and means for limiting the movement of said rollers toward the spindle.

20. A speed indicator comprising a slotted vertical spindle, the slot increasing

in width upwardly, a carrier free to travel 65 parallel with and alongside of the spindle, friction rollers mounted on the carrier in contact with the surface of the spindle and inclined thereto, means for limiting the movement of said rollers toward the spindle, 70 and yielding means for forcing said rollers toward the spindle.

21. A speed indicator comprising a slotted spindle, a carriage slidable thereon, the slots in said spindle being on opposed sides 75 thereof and increasing in width from one end, and frictional contact rollers on the carriage on opposed sides of the spindle, said rollers being adapted to be in contact with the surface of the spindle but to be out 80 of contact therewith when in line with the slots.

22. A speed indicator comprising a slotted spindle, a carriage slidable thereon, the slots in said spindle being on opposed sides 85 thereof and increasing in width from one end, and frictional contact rollers on the carriage on opposed sides of the spindle, said rollers being inclined to the axis of the spindle and adapted to be in contact with the 90 surface of the spindle but to be out of contact therewith when in line with the slots.

23. A speed indicator comprising a slotted spindle, a carriage slidable thereon, the slots in said spindle being on opposed sides there- 95 of and increasing in width from one end, and frictional contact rollers on the carriage on opposed sides of the spindle, said rollers being inclined to the axis of the spindle and adapted to be in contact with the surface of 100 the spindle but to be out of contact therewith when in line with the slots, and yielding means for pressing said rollers toward the spindle from opposed sides.

24. A speed indicator comprising a slotted 105 spindle, a carriage slidable thereon, the slots in said spindle being on opposed sides there- of and increasing in width from one end, frictional contact rollers on the carriage on opposed sides of the spindle, said rollers being inclined to the axis of the spindle and adapted to be in contact with the surface of the spindle but to be out of contact therewith when in line with the slots, and yielding means for pressing said rollers toward 110 the spindle from opposed sides, and means for limiting the movement of said rollers toward the spindle.

25. A speed indicator comprising a slotted 120 spindle, a carriage slidable thereon, the slots in said spindle being on opposed sides there- of and increasing in width from one end, frictional contact rollers on the carriage on opposed sides of the spindle, said rollers being inclined to the axis of the spindle and adapted to be in contact with the surface of 125 the spindle but to be out of contact therewith when in line with the slots, yielding

means for pressing said rollers toward the spindle from opposed sides, means for limiting the movement of said rollers toward the spindle, and means for adjusting the inclination of the rollers with respect to the spindle.

In testimony whereof, I affix my signature

in the presence of two witnesses this 13th day of April, 1914.

GUY W. BLACKBURN.
